UNITED STATES PATENT OFFICE.

CHARLES PERKINS, OF BRIDGEWATER, MASSACHUSETTS.

PNEUMATIC TURBINE-GRINDER.

1,143,064.

Specification of Letters Patent. Patented June 15, 1915.

Application filed November 20, 1914. Serial No. 873,124.

To all whom it may concern:

Be it known that I, CHARLES PERKINS, a citizen of the United States, residing at Bridgewater, county of Plymouth, State of Massachusetts, have invented an Improvement in Pneumatic Turbine-Grinders, of which the following description, in connection with the accompanying drawing, is a specification, like characters on the drawing 10 representing like parts.

This invention relates to hand tools and consists of a novel construction of a turbine grinder.

The object of this invention is to obtain a 15 portable and manually operable power driven grinder.

Another object is to provide a rotary grinder in which the means for imparting rotation are adjacent the tool.

20 Another object is to secure an easily manipulated light weight compressed air turbine grinder whose moving elements are dirt-proof, which has few parts, and is simple in construction, and can be produced at 25 small expense.

In order to give an understanding of this invention, there is illustrated in the drawings a selected embodiment of the same which will now be described.

30 Figure 1 is a median section of the grinder; Fig. 2 is an elevation of the parts shown in Fig. 1, looking from the right hand end, with the ring plate partly broken away; Fig. 3 is a section on the line 3—3, Fig. 1; 35 Fig. 4 is a section on the line 4—4, Fig. 2.

This novel construction of the grinder is formed in this selected embodiment with a housing 1 in which is revolvably mounted a rotor shaft 2 and the impulse wheel 3 having an annular web 4 upon the periphery 5 of which are secured the vanes 6. Radial ribs 7 are cast integral with the main housing 1 and give rigid support to the part of the housing containing the impulse wheel.

45 The air intake face of the housing is closed by means of the cover 8. The housing has cast integral therewith the ears 9 containing threaded recesses while the cover has similar ears 10 bored to receive the screws

50 11 which are secured in the threaded recesses of the housing ears 9 and the cover thereby secured to the housing. The cover 8 has a central extension 12 which affords a bearing for the rotor shaft 2 and a housing 55 for the air supply duct 13. This air duct 13 terminates in a coupling to which may be

secured a flexible tube or other flexible means for furnishing an air supply. The air duct 13 terminates at its inner end in the transverse air pipe 14 which leads in both directions to the annular channel 15 in the cover. The ring plate 16, secured to the cover 8 by the screws 17, closes the channel 15 and thus forms an annular air pipeway. The ports or nozzles 18 cut in the cover 8 form the means for directing the compressed air against the vanes 6. The nozzles 18 in this selected embodiment are of a diverging conical type and, as shown in Fig. 4 lead off at an angle of approximately 20° from the air channel 15. The compressed air is thus directed tangentially to impinge upon the vanes 6 of the turbine wheel. There are four such nozzles shown in the accompanying drawings, and they are equi-distantly located in the channel 15. The vanes 6 of the impulse wheel are curved and the compressed air impinging thereon drives the wheel, the air being then exhausted through the exhaust ports 19 which are open to the atmosphere. These exhaust ports are formed by cutting narrow openings in the face of the wheel housing opposite the cover. These ports are placed a short distance beyond each of the air intakes or nozzles and thus give the compressed air a working distance between the intake and the exhaust sufficient to utilize the expansive force of the air.

The rotor shaft 2 terminates in a coupling 90 secured to the grinder shaft 21 while the housing 1 terminates in a threaded flange 22 which is secured in a similarly threaded recess in the casing 23 of the grinder shaft. This grinder shaft projects from its casing 95 and has a collar 24 secured thereon by a pin 25, the collar being held against the flange 26 of the grinder shaft casing. The shaft end 28 is threaded and a grinder 29 is slipped thereon against the washer 30 and retained by the check nut 31. The grinder shaft casing 23 and the integral extension 12 of the cover 8 form handles by means of which the grinder is manipulated by the operative.

105 The method of operation is extremely simple. The air, under compression and supplied from any suitable source, is introduced into the air duct 13, whence it travels to the transverse air-way 14 leading in two directions to the circular pipe 15. The nozzles 18 of the diverging type permit a slight

expansion of the air as it passes to the vanes 6 of the turbine wheel wheron it impinges tangentially. The air has an effective working area from the tip of the nozzle to the 5 beginning of the adjacent and opposedly positioned exhaust ports. As the successive vanes pass the exhaust ports the spent air is exhausted into the atmosphere. The turbine is mounted upon, and is rotatable with, the 10 rotor shaft which in turn drives, through the medium of the coupling 20, the shaft upon which the grinding surface is secured.

There is thus produced an efficient portable power-driven grinder which can be 15 easily and effectively operated at varying distances from the source of power. The grinder has few elements and those which are rotatory have dirt-proof bearings. It is compact, light and small—in practice, the 20 preferable size of the wheel is from four to nine inches. The linear speed of the grinding surface is high—accomplishing the work quickly and efficiently. It is inexpensive to manufacture, not easily deranged, and can 25 be manipulated with facility.

This apparatus is especially efficient as a means for brushing or scrubbing hard surfaces, as for example building and other 30 walls and for removing rust from iron surfaces. A stiff wire brush may be attached, for this purpose, to the threaded shaft end.

It is obvious that this tool may be used for buffing, boring or drilling by simply securing the appropriate tool on the threaded shaft end.

Having fully described my invention, what I claim as new and desire to secure by Letters Patent is:

1. A portable tool comprising a rotor, a 40 rotor shaft, a housing for said rotor, a cover for said housing, an annular conduit in said cover, a plurality of ports in said cover for directing an elastic fluid to said rotor, a plurality of exhausts in said rotor housing, 45 an extension to said cover, comprising a casing for said rotor shaft and a duct for directing an elastic fluid to said annular conduit and means for supplying an elastic fluid under pressure to said duct.

2. A portable tool comprising a rotor, a 50 rotor shaft, a housing for said rotor, a cover for said housing, an annular conduit in said cover, a plurality of ports in said conduit adjacent the periphery of said rotor for directing tangentially to its vanes an 55 elastic fluid, a plurality of complementary exhaust orifices in said housing, said orifices being offset with respect to said ports whereby an elastic fluid is given an effective working distance along the periphery of 60 said rotor, a duct in said cover for directing an elastic fluid to said conduit and means in said cover for affording a plurality of passages for an elastic fluid from said duct to said conduit and means for supplying an 65 elastic fluid under compression to said duct.

3. A portable power tool comprising a 70 rotor, a rotor shaft, a housing for said rotor, a cover for said housing, said cover containing an annular conduit, a pipe having a plurality of passages thereto, a duct for directing a supply of an elastic fluid under compression to said pipe and flexible means secured to said duct whereby a supply of an 75 elastic fluid may be afforded to said portable power tool.

4. A power hand tool comprising a rotor, a rotor shaft, a casing for said rotor, a cover for said casing containing an intake pipe for an elastic fluid, a two-way duct leading from 80 said intake, an annular channel in which said duct terminates, a ring plate secured to said cover forming with said channel an annular conduit, nozzles in said conduit for directing the elastic fluid against the rotor 85 whereby said rotor is actuated, segmental orifices in said housing adjacent the side of the rotor opposite said cover for exhausting the fluid and means for supplying an elastic fluid under compression to said intake. 90

In testimony whereof, I have signed my name to this specification, in the presence of two subscribing witnesses.

CHARLES PERKINS.
